H. LEITNER

MECHANISM FOR VARYING THE PITCH OF SCREW PROPELLERS

Filed April 21, 1924

Inventor
Henry Leitner
By George A. Prout-
aty.

UNITED STATES PATENT OFFICE.

HENRY LEITNER, OF LONDON, ENGLAND.

MECHANISM FOR VARYING THE PITCH OF SCREW PROPELLERS.

Application filed April 21, 1924. Serial No. 708,095.

To all whom it may concern:

Be it known that I, HENRY LEITNER, a subject of the King of Great Britain, residing at Regent House, Kingsway, London, 5 England, have invented new and useful Improvements in Mechanism for Varying the Pitch of Screw Propellers, of which the following is a specification.

My invention relates to mechanism for 10 varying the pitch of screw propellers in which the propeller blades have cylindrical ends or stems which permit of their rotation round their own axes, teeth being provided on each blade stem in the form of a worm-wheel concentric with the stem and engaging a worm, which is geared by means, such as spur-gearing, to a common wheel which I term a master-wheel. Every blade is thus geared to this master-wheel so that 20 if this wheel be rotated in either direction, each blade will be rotated on its axis through a certain angle, thereby varying the pitch of the whole propeller. Means are also described in the said specification 25 whereby the master-wheel can be rotated at will.

Now, the object of this invention is to provide improved means for rotating the master-wheel either at the will of the operator, or automatically, or both, and to this end I proceed as follows, that is to say, concentric with the master-wheel I provide a spur-wheel which may be locked to, or geared to, or otherwise suitably held to the 30 said master-wheel and meshing with the teeth of this spur-wheel I provide a toothed quadrant fulcrumed to the hub of the propeller. This quadrant may or may not be balanced in such a manner that the centrifugal forces acting thereon are neutralized, or 35 the movement of the quadrant by centrifugal force may be utilized to automatically rotate the master spur-wheel.

By this construction when the quadrant 40 is swung on its fulcrum it will rotate the wheel engaging with it, which in turn will rotate the master-wheel and thereby the propeller blades through the worm-gearing.

Suitable mechanism for swinging the 45 quadrant comprises a rail or roller fixed to some stationary part of the engine or machine carrying the latter, but movable so that as the propeller revolves, the rail or roller contacts with some portion of the 50 quadrant and rocks it on its fulcrum to alter the pitch of the propeller blades. An-

other rail or roller applied in the opposite direction will turn the propeller blades in the reverse direction. These rails or rollers may be moved by suitable means by hand. 60

To enable the invention to be fully understood I will describe it by reference to the accompanying drawing, in which:—

Figure 1 is an elevation of a portion of the hub of a two-bladed screw-propeller, the 65 blades of which are variable for pitch, having my improvements applied thereto.

Figure 2 is a sectional view at right angles to Figure 1 and

Figure 3 is a plan with certain parts removed. 70

a is the hub of the propeller and *b*, *b* are the cylindrical stems of the blades which are located and turn in the bearings *c*, *c*. *d*, *d* are the worm-wheels on the said stems and 75 *e*, *e* are the worms gearing therewith and rotatable by spur-wheels or pinions *f*, *f* engaging the common or master spur-wheel *g*.

h is the spur-wheel concentric with the master-wheel *g* and *i* is the quadrant the 80 teeth of which mesh with those of the wheel *h*, so that when the said quadrant is rocked on its fulcrum it will effect the rotation of the said wheel *h* and consequently rotate the master-wheel *g* to effect the equal rotation of both propeller blades to adjust the 85 pitch angle.

j is one of the rollers whereby the quadrant *i* is rocked on its fulcrum, the said roller being moved or interposed in the path 90 of another roller *k* carried on the said quadrant so as to contact therewith and effect the required movement. This roller *j* is shown as being carried by a screwed bolt *l* which can be moved longitudinally 95 by a nut *m* engaging therewith and adapted to be rotated by a rope or chain *m'* controlled or moved in any suitable manner by hand. For moving the quadrant in the opposite direction to that effected by the roller *k*, another roller, not shown, similar to the roller *j* is employed which acts upon a second roller *n* on the quadrant, these two last mentioned rollers being in a different plane from that of the rollers *j*, *k*. 100

Although I have described the wheel *h* as being concentric with the master-wheel *g* it may be geared thereto and, instead of the quadrant, I may employ a complete toothed wheel or a toothed rack of a shape in the 110 nature of a cam.

Means may also be provided whereby as

- the engine increases its speed the quadrant in engagement with the spur-wheel causes the latter to rotate by virtue of the increase of centrifugal force set up in the parts.
- 5 The blades consequently being made to increase their pitch so as to offer more resistance to rotation, and vice versa, thus governing the engine or propeller speed. Such means may comprise a weight attached to
- 10 one side of the quadrant and exerting a pull thereon by centrifugal action, a compression or like spring being arranged on the opposite side of the quadrant to return it to its normal position.
- 15 Although the invention has been described in connection with two-bladed propellers it is to be understood that it may be applied to propellers having three or four blades.
- 20 Claims:
1. Mechanism for varying the pitch of screw propellers including a propeller hub, a master wheel, a spur-wheel connected to said master wheel, a toothed member in gear with said spur-wheel and pivoted to said propeller hub, and means interposed in the path of said toothed member as it is rotated by the propeller hub to cause said toothed member to rock on its pivot in either direction whereby the propeller blades are rotated around their axes.
  2. Mechanism as claimed in claim 1, wherein said spur-wheel is mounted concentrically with said master wheel, and the toothed member is in the form of a quadrant.
  3. Mechanism as claimed in claim 1 wherein said means for causing the toothed member to rock on its pivot, includes a stationary member and rollers on said toothed member adapted to contact with said stationary member.

HENRY LEITNER.
